HEATER

Albert Sorensen, Washington, D. C.

Application August 24, 1934, Serial No. 741,303

8 Claims. (Cl. 122—356)

The present invention relates to heaters for liquids, sometimes classified as tubular heat interchangers or heaters of the water tube type.

The principal object of the invention is to provide water heaters for use in connection with the radiators of room heating systems, and for supplying hot water for domestic and analogous purposes, which are light in weight, comparatively inexpensive, and adapted to thoroughly heat water with minimum consumption of gas or other heating medium. By way of example, the heaters as units may be located in close proximity to the radiators so that there will be no appreciable loss of heat in the basement, walls, etc., thru which pipes leading to the radiators may run. Two or more units may be used as a part of the heating system of a house, or portion thereof. These units may be located adjacent opposite walls thereof, say adjacent the north and south walls, and that unit supplying heated water to the radiators located on the north side of the building, supplied with more fuel than that located on the south side, so as to adequately heat the normally colder north portion of the house. Or, the units may be installed each to heat separate apartments in a house, or supply hot water for domestic and other purposes to different apartments of the same house.

Another object of the invention is to provide in a water heater of the water tube type an arrangement whereby the water tubes provide a baffling arrangement, avoiding the use of angles, sheets or strips of metal, or tiles of refractory material to complete the baffles adjacent the upright walls of the casing. Such metal angles, sheets or strips are likely to burn away very rapidly since they contain no water and are subjected to extreme high temperature. The tiles are comparatively heavy for support on the tubes and likely to damage the tubes by abrasive action as the tubes move relative to the tiles due to changes in temperature.

Another object of the invention is to provide a heater which is light in weight, which facilitates ease of handling, ready passage through small doorways, halls, etc., and which may be supported near or suspended from the ceiling of the basement and closely subjacent the radiators or water outlets connected therewith.

A still further object of the invention is to so shape and form the heater and its casing that it is of unit form whereby two or more units may be connected so as to provide an assembly which will be of the desired capacity.

Other objects and advantages of the invention will appear in the following detailed description, taken in connection with the accompanying drawing, forming a part of this specification, and in which drawing:

Figure 1 is a front elevation of a water heater constructed according to the present invention.

Figure 2 is a rear elevation of the same, a portion of the casing being broken away to disclose details.

Figure 3 is a central vertical sectional view through the heater, portions of the water tubes being broken away and shown in section to disclose a typical connection of the ends of the tubes with heaters.

Figure 4 is an enlarged horizontal sectional view on the line 4—4 of Figure 3.

Figure 5 is a view similar to Figure 2 but showing a modification.

In the drawing, where like characters designate like or similar parts throughout the views, A designates a casing providing a heating chamber B and a stack or off-take flue C for the waste products of combustion; D water tube units, each preferably comprising a lower header E and an upper header F, and a group of water tubes G connecting the headers; H a manifold connecting the adjacent ends of lower headers E as shown in Figures 2 and 4; J a manifold connecting the adjacent ends of upper headers F as shown in Figure 2; K an inlet pipe to the manifold H; L an outlet pipe from manifold J; M detachable caps for the ends of headers E opposite to manifold H; N detachable caps for the ends of headers F opposite to manifold J; O a suitable burner, such as one for gas or oil; and P a feed pipe leading to burner O.

The casing A is preferably shaped to provide the heating chamber B of elongated upright shape, rectangular in horizontal cross section, so that the water tubes G may be bent to follow a tortuous course in the heating chamber from the lower portion to the upper portion thereof, thereby permitting long tubes to be arranged in a relatively small chamber. The casing A may comprise a main body portion 6 and a cap 7, the latter preferably frusto-pyramidal in shape and connected to the stack or flue C in a manner to direct the gases arising in the heating chamber to the flue, as shown in Figure 3. The main body 6 may be formed of elongated, rectangular upright front and rear walls 8 and 9, and opposite side walls 10 and 11, respectively. In the example shown the walls 9, 10, and 11 may comprise an integral sheet of metal 12, bent along vertical lines, and lined at the interior with wall sections 13, 14, and 15 of 55

yieldable heat insulating material, such as asbestos; and the front wall 8 secured to the side walls 10 and 11, as by means of screws 16 extending through vertical flanges 17, formed at right angles along the upright margins of front wall 8, the screws having threaded connection, in the usual way, with the walls 10 and 11. The front wall may comprise an outer sheet metal main body portion 18 provided with an elongated, vertical, rectangular opening 20, having a door or removable section 21 to afford access to the burner O and to the tubes G. In the example shown, a small removable plate 22, held in place by clips 23, is provided below the door or removable section 21 to facilitate placing or removal of the feed pipe P. The metallic front 18, door or removable section 21, and removable plate 22 are provided with wall sections of yieldable heat insulating material designated generally by character 24, such as sheet asbestos.

From the foregoing it will be observed that the casing A includes opposite upright parallel walls 13 and 24 and opposite upright parallel walls 14 and 15 of yieldable heat insulating material, which material may cooperate with the headers E and F and the water tubes G to prevent hot gases arising from the burner O finding their way to the stack or flue C, except by following a tortuous course, as hereinafter set forth.

Each the front wall 8 and the rear wall 9 is provided with openings 26 adjacent its lower margin, and openings 27 adjacent its upper margin through which the end portions of the headers E and F, respectively, extend, as shown more in detail in Figures 3 and 4. These headers are preferably tubular in shape, screw threaded as at 28, at opposite ends and engage the wall portions 14 and 15, so as to prevent passage of hot gases, issuing from the burner, passing vertically adjacent the walls 10 and 11, throughout their length.

Each water tube unit D comprises a lower header E and a companion upper header F, and a group 30 of water tubes G connecting the headers. It is preferred to make these water tube units interchangeable, that is, altho the tubes are bent to a serpentine shape, the two units may be arranged so that the groups of water tubes will have the greater portion of the length of the tubes of one group in spaced parallel relation to the similar portion of the tubes of the adjacent group, whereby gases of combustion follow a tortuous course between the groups of water tubes and sweep the tubes longitudinally over substantially their entire length, as shown in Figure 3. By way of example, each tube G may be provided with an elbow 31 extending from that side of its one header that faces the other header, or, in other words, is in the plane common to the longitudinal axes of the companion headers. From the elbow 31 may extend a straight run of tubes 32; then a relatively short return bend 33; then another straight run 34; then a relatively large return bend 35; then another straight run 36, connected to another relatively short return bend 37, which has connection with the other header through a straight run 38. The latter straight run is preferably in a plane nearly at right angles to the first mentioned plane, as shown in Figures 3 and 5. Thus when the two water tube units are assembled, the relatively short return bend 37 of one of the water tube units may be near the bottom of the heating chamber B and in parallel relation to the elbows 31 of the other water tube unit, and so on,—the straight runs 32 and 36, and 34 par-

alleling each other, and the return bends 33 and 35 paralleling each other.

The manifolds H and J may each be of like construction, preferably made of pipe fittings, such as a T 40, nipples 41 at opposite outlets thereof, and elbows 42 each provided with a union 43, connected to the nipples 41, and with the unions 43 having detachable connection with the screw threaded end portions 28 of the headers.

Inlet pipe K has connection with the T of manifold H, as shown in Figures 2 and 4, and outlet pipe L has connection with the T 40 of manifold J.

The caps M have detachable connection with the screw threaded end portions 28 of headers E at the ends thereof opposite to manifold H, while the caps N have detachable connection with the screw threaded end portions of headers F at the end portions opposite manifold J. It is to be noted, however, that these manifolds and caps are interchangeable, that is, the caps may be adjacent the rear wall 9 of the housing, and the manifolds in front, where it would be desirable to provide elbows 42 with each a relatively long leg, so that the door or removable section 21 may be opened, or either the manifold H or J may be at the top or bottom of the front,—whichever arrangement may be found most suitable, and according to the location of available pipes leading to and from radiators, water supply connections, stand pipes, etc.

The burner O is disclosed merely by way of example for it is to be understood that this burner may be suitable for use with a gaseous or liquid fuel, or a vapor fuel. In the example shown it is resting upon oppositely disposed flanges 45 secured to the walls 8 and 9. The feed pipe B is provided with a valve 46 of any suitable character and the feed pipe extends through an opening 47 in the plate 22, this opening having communication with the lower margin 48 of the plate, so that the latter may be lifted from the clips 23, when the door or removable section 21 is in an open position.

The lower portion of casing A is preferably open to the atmosphere as at 49 so that access may be had to the burner, for lighting purposes through such open bottom.

An important feature of the present invention is that the outermost tubes 50 of each group 30 are in side contact with the walls 13 and 24 of yieldable heat insulating material, so that they exclude passage of hot gases arising from the burner finding exit from the casing by passing vertically along the walls 8 and 9. The water tubes and headers, because each group of serpentine tubes are arranged in side by side contact with each other through at least the greater portion of their length, and the walls of yieldable heat insulating material, confine the gases of combustion to a tortuous course, as shown by the arrows in Figure 3, sweeping the tubes longitudinally, over substantially their entire length, and requiring no angles, sheets or strips of metal, or tiles as baffles.

Replacement of either or both of the water tube units D may be readily accomplished by manipulation of the unions 43, the removal of one or more of the caps M and N, and disconnection of the front wall 8 from the remaining portion 6 of the cabinet.

It is not essential that the water take a course as indicated by arrows in Figure 2. If desired, the lower headers E may be connected by a pipe length 55 and elbows 56, provided with unions 57 75

for connection with the adjacent ends of the headers E, and an inlet pipe 58, and outlet pipe 59 may have connection with the adjacent ends of the upper headers F, as shown in Figure 5, whereupon the flow of liquid will be downwardly through one of the water tube units and then upwardly through the other water unit D.

I claim:

1. In a water heater, the combination of a casing including opposite upright parallel walls of yieldable heat insulating material, and at least two groups of water tubes, each group comprising a plurality of serpentine tubes arranged in side by side contact with each other throughout at least the greater portion of their length, the outermost of the tubes of each group in side contact with said walls of yieldable heat insulating material, and the groups of water tubes arranged with the greater portion of the length of the tubes of one group in spaced parallel relation to the similar portion of the tubes of the adjacent group whereby gases of combustion follow a tortuous course between the groups of water tubes and sweep the tubes longitudinally over their entire length.
2. In a water heater, the combination of a casing including opposite upright parallel walls, and at least two groups of water tubes, each group comprising a plurality of serpentine tubes arranged in side by side contact with each other throughout at least the greater portion of their length, and the groups of water tubes arranged with the greater portion of the length of the tubes of one group in spaced parallel relation to the similar portion of the tubes of the adjacent group whereby gases of combustion follow a tortuous course between the groups of water tubes and sweep the tubes longitudinally over their entire length.
3. In a water tube heater, the combination of a casing, providing a heating chamber, including opposite upright parallel walls, two pairs of headers, each pair including a lower header and a companion upper header, said headers extending through said heating chamber and through and extending beyond the outer faces of said opposite walls of the casing, and the lower and upper headers of each pair of headers in laterally spaced parallel relation, and a group of water tubes for each companion lower header and upper header, each group comprising a plurality of serpentine tubes arranged in parallel, side by side, contacting relation throughout at least the greater portion of their length and connected to their respective headers with the ways of the headers, and the groups of water tubes arranged with the greater portion of the length of the tubes of one group in spaced parallel relation to the similar portion of the tubes of the adjacent group whereby gases of combustion follow a tortuous course between the groups of water tubes and sweep the tubes longitudinally over their entire length.
4. In a water tube heater, the combination of a casing, providing a heating chamber, including opposite upright parallel walls, two pairs of headers, each pair including a lower header and a companion upper header, said headers extending through said heating chamber and through and extending beyond the outer faces of said opposite walls of the casing, and the lower and upper headers of each pair of headers in laterally spaced parallel relation, a group of water tubes for each companion lower header and upper header, each group comprising a plurality of serpentine tubes arranged in parallel, side by side, contacting relation throughout at least the greater portion of their length and connected to the lower and upper headers, and with the outermost tubes of each group in side contact with the other opposite walls of yieldable heat insulating material, and the groups of water tubes arranged with the greater portion of the length of the tubes of one group in spaced parallel relation to the similar portion of the tubes of the adjacent group whereby gases of combustion follow a tortuous course between the groups of water tubes and sweep the tubes longitudinally over substantially their entire length.
5. As an article of manufacture, a unit for water heaters comprising a pair of tubular headers arranged in parallel relation, and a plurality of serpentine tubes connecting said headers laterally and with their ways in communication with the ways of said headers, said tubes in side by side, contacting relation throughout their entire length between the headers.
6. In a water heater, the combination of a cas-

ing providing an elongated upright heating chamber, rectangular in horizontal cross section and including opposite upright parallel walls of yieldable heat insulating material, two pairs of headers, each pair including a lower header and a companion upper header, said headers of one pair horizontally disposed in the heating chamber and contacting with one of said walls of yieldable heat insulating material adjacent the lower and upper portions thereof, and the companion headers of the other pair similarly disposed in the chamber and contacting with the opposite wall of yieldable heat insulating material, and a group of water tubes for each companion lower and upper head-

er, each group comprising a plurality of serpentine tubes arranged in parallel, side by side, contacting relation throughout at least the greater portion of their length and connected to the lower and upper headers, and the groups of water tubes arranged with the greater portion of the length of the tubes of one group in spaced parallel relation to the similar portion of the tubes of the adjacent group whereby gases of combustion follow a tortuous course between the groups of water tubes and sweep the tubes longitudinally over substantially their entire length. 5 10

ALBERT SORENSEN.
